UNITED STATES PATENT OFFICE.

LOUIS PAPENBROK, OF ADDISON, ILLINOIS.

ATTACHMENT FOR EXPLOSIVE-ENGINES.

1,115,967.

Specification of Letters Patent. Patented Nov. 3, 1914.

Application filed March 12, 1914. Serial No. 824,299.

To all whom it may concern:

Be it known that I, LOUIS PAPENBROK, a citizen of the United States, residing at Addison, in the county of Dupage and State of Illinois, have invented certain new and useful Improvements in Attachments for Explosive-Engines, of which the following is a specification.

This invention relates to improvements in attachments for explosive engines and more particularly to gasoline engines and its object is to produce an attachment by means of which a cheap grade of fuel can be fed to the engine after the engine has been primed with a good grade of fuel.

With the foregoing and other objects in view the invention consists in the combination and arrangement of parts to be herein-after fully described in the following specification, pointed out in the claim and illustrated in the accompanying drawings which form a part of said specification and in which—

Figure 1 is a side elevation of my attachment secured to the cylinder head of a gasoline engine. Fig. 2 is a section taken on line 2—2 of Fig. 4. Fig. 3 is a top plan of a portion of Fig. 2. Fig. 4 is a plan view of the attachment. Fig. 5 is a section taken on line 5—5 of Fig. 4.

Like reference characters indicate corresponding parts throughout the several views.

The reference numeral 1 indicates the cylinder head of a gasoline engine and the same is provided with the valve 2. To the cylinder head an approximately semi-circular casing 3 is secured which extends above and below the valve and is provided with a gasoline intake pipe 4 and a drain plug 5.

A drain pipe 6 extends through the floor 7 of the casing to a point above the valve in the cylinder head and said drain pipe is capable of registration with the mouth of a swing pipe 8 which also rises from the floor 45 of the casing to a point above the valve and which is supported in and movable horizon-

tally by a support comprising a strap 9 connected to a stem 10 which extends through the top of the casing 3 and there is provided with a handle 11. The top of the 50 casing is formed with a curved slot 12 through which the stem 10 extends and this slotted portion of the casing limits the movement of the stem 10 and consequently of the swing pipe. The swing pipe 8 communicates with a reservoir (not shown) which contains a cheap grade of fuel.

Operation: To start the engine gasoline is admitted to the casing 3 through the pipe 4 until the casing is filled above the level of 60 the valve which valve is opened and the engine primed. After the engine is warmed up the supply of gasoline is shut off and the swing pipe, which is constantly running cheap fuel normally into the drain pipe 6, is 65 swung out of connection with the drain pipe and the fuel therefrom permitted to run into the casing 3 and used to drive the engine instead of the high grade oil by which it is started.

70 What is claimed is:—

In a carbureter for explosive engines, the combination of a casing provided with an outlet, a valve for controlling said outlet, said casing extending above and below said 75 valve, a gasoline intake pipe for said casing, a swing pipe for cheap fuel entering through the floor of the casing and extending above the valve level, a drain pipe extending above the level of the valve normally in engagement with the mouth of said swing pipe, means for moving said swing pipe out of 80 normal position and a drain plug for said casing.

In testimony that I claim the foregoing 85 as my own I have hereto affixed my signature in the presence of two subscribing witnesses.

LOUIS PAPENBROK.

Witnesses:

WILLIAM FIENE,
EDW. ROSENWINKEL.
